CARD FEEDING AND HANDLING DEVICE

Clair D. Lake, Binghamton, N. Y., assignor, by
mesne assignments, to International Business
Machines Corporation, New York, N. Y., a cor-
poration of New York

Application June 29, 1932, Serial No. 619,903

9 Claims. (Cl. 209—110)

The present invention relates broadly to card controlled machines in general and more particularly to those adapted to sort record cards such as are used to control the operation of the well known Hollerith type of tabulating machine.

The primary object of the invention is to provide a novel means for distributing the individual cards of a plurality of groups of cards into a series of sorting pockets, so that the cards of each group having the same sequential allocation will be sorted into the same pocket. This may be better explained by an illustrative example taken from industrial practice. In certain industries a group of cards, let us say eight, for example, are gang punched with a workman's number and are serially numbered with the dates of the days of a particular working period. A similar group is punched for each man in a department and after the punching and numbering operations are complete, there will be a number of such groups of cards which it is desirable to rearrange so that all cards of the first day comprise one group, all cards of the second day comprise another group, etc. Heretofore, this rearrangement has been effected by manual means which obviously is tedious and time consuming.

The present invention contemplates the rapid rearrangement of such groups of cards, each having a similar number of individual cards similarly arranged in the same sequential order. Use is made of a well known sorting machine of the type disclosed in Patent No. 1,741,985, issued to E. A. Ford on December 31, 1929 in which a plurality of sorting pockets are employed. The invention provides mechanism for automatically feeding each card of the first group to a different pocket, and then feeding the corresponding sequentially allocated cards of the next group to the same pockets and in the same order. After all groups have passed through the machine each pocket will contain all the cards relating to a particular date.

A further object of the machine provides for the ready readjustment of the machine for the performance of usual card sorting operations.

In Fig. 1 of the drawings there is shown a preferred form of embodiment of the invention, the mechanical elements of which have been diagrammatically illustrated and show the elements of a sorting machine as set forth in greater detail in Patent No. 1,741,985.

Fig. 2 is a fragment of a record card.

Fig. 3 is a partial circuit of a modified form of the invention.

Before proceeding with the description of the

invention the sorting machine will be briefly explained as to its general principles. The drawings show an electrically controlled sorting machine in which the sorting of the record cards is accomplished through the medium of a sorting magnet 11 under the control of a brush relay 10 which, jointly with the sorting magnet, is in circuit with the analyzing brush 22 and, with the sorting magnet, receives exciting current from a source 17 as soon as a hole is encountered in the card column analyzed. According to the point of time at which the energization of the sorting magnet 11 takes place, the armature 23, upon which the ends of the tongues 24 of the guide blades leading to the card receiving pockets 25 rest, determines the destination of the card being analyzed.

The ends of the tongues 24 are spring-urged downwardly upon the armature 23 so that during the card analyzing cycle the record card R is guided between the ends of the tongues 24 and the armature 23, with the result that on the energization of the sorting magnet 11, only as many tongues 24 are lowered by the armature as do not overlie the record card, while the remaining tongues 24 are kept in raised position by the card. For this purpose, there is provided a fixed bar 26, parallel to, and on a level with, the armature 23, in its normal position, arranged to support the record card after the armature is lowered. It may be mentioned that the time of energization of the sorting magnet depends upon the position of the hole in the card column, each of which has twelve index point positions, so that the cards may be guided selectively into any one of twelve sorting pockets 25.

Through the downward movement effected by energization of the sorting magnet, the tongues 24 disengaged from the card R produce a gap between the last tongue caught by the record card 40 and the next adjacent tongue, moved downwardly along with the armature 23, into which gap the record card is conveyed and thereafter guided to the coordinated sorting pocket by means of the usual feeding rollers 27.

If it should happen that there is no perforation in the card column analyzed, the magnet 11 will not be energized and the card will pass beneath all of the tongues 24 and will be guided to a thirteenth pocket 25R known as the "reject" 50 pocket. The card feeding mechanism comprises a picker 28, horizontally reciprocable to feed cards, singly, from the bottom of a stack 29 to a pair of feed rollers 30 which advance the card to and between brush 22 and contact roller 30. 55

The drive of the machine is effected by means of a motor 31 which is under control of motor relays 32 and 33 in such a way that upon the energization of the same, the motor is connected to the current source 17. Energization of relays 32 and 33 is effected through depression of the start key to close start contacts S, setting up a circuit from negative side of source 17, wire 34, contacts S, card lever relay 35, relays 32 and 10 33, wire 36 to positive side of source 17. Relay 35 closes its point 35a in series with the usual card lever contacts 37 and forms a shunt circuit around contacts S so that as long as cards continue to run through the machine, the energization 15 of relays 35, 32 and 33 will be maintained. After the last card has passed the brushes 22 and the card lever contacts 37 have opened, or the stop key contacts ST have been opened, the de-energization of the relays 35, 32, 33 is effected, in consequence 20 of which the motor 31 will be disconnected from the current source 17 and the machine will thereafter come to rest.

In order to secure proper operation of the sorting machine, it is necessary that the sorting magnet remain energized from the moment at which energization takes place until the last index point position in the card column has passed from beneath the analyzing brush 22. The winding of the brush relay 10 is connected in series with the sorting magnet 11 and is energized therewith as soon as a hole is encountered in the card column analyzed and corresponding to the adjustment of the contact segments 12 of commutator 13. There are twelve segments 12 and these successively contact with a brush 14 which is connected by a wire 15 to the common brush of roller 30. Commutator 13 also has a common wiping brush 16 connected to the current source 17 through a wire 18 and resting upon a metallic ring 19 which is electrically connected to a commutator segment 20 which cooperates with a brush 21. The commutator 13, which is synchronized with the speed of passage of the cards, moves its segments 12 past brush 14, one for each 45 index point position of the card.

If, during the passage of the card past the usual sorting brush 22, the card hole in the column analyzed coincides with wiping of a segment 12 of the commutator 13, then, as may be seen from the drawings, energization of the brush relay 10 and sorting magnet 11 will be effected.

The foregoing outlines the usual operation of a sorting machine and if switches 38 and 39 are left in open position, ordinary sorting may be performed by the machine. With these switches closed, and the sorting brush raised out of engagement with the contact roller 30 the machine will be prepared to distribute cards in accordance with the invention. Additional commutators X, Y and Z are provided which may be mounted coaxially with commutator 13 to make one revolution per card cycle therewith. Commutator brushes 40 and 41 may also be carried by the same shaft to cooperate with stationary commutators 40a and 41a to control circuits in a manner to be presently explained.

Assuming that several groups of cards, each containing, let us say, eleven cards, have been placed in the stack 29, depression of the start key will cause feeding of the first card from the bottom of the stack, advancing its leading edge toward the tongues 24. After the card lever contacts 37 are closed thereby (which occurs before the cards reach the first tongue 24) a circuit is completed when the leading edge of the

card is in the dotted line position as shown in the drawings, as follows: from negative side of source 17, wire 42, contacts 37, switch 38, wire 43, brush 40, the "11" segment of commutator 40a, wires 44 and 45 to the "11" segment of commutator 41a, brush 41, wire 46, switch 39, wire 47, brush relay 10, sorting magnet 11, wire 48 to positive side of source 17. The two tongues in advance of the card will thereupon be lowered and the card will continue into the gap so provided and will be conducted to the "11" sorting pocket 25.

At the same time, a parallel circuit will extend from wire 44, through a relay A, relay A', wire 48, to the positive side of source 17. Relay A will close its points to set up a holding circuit for relays A and A' as follows: from positive side of source 17, wire 49, relays A', A, points of relay A, wire 50, points 51a of a relay 51, wire 43, switch 38, contacts 37, wire 42 to negative side of source 17.

On the next card cycle, when the leading edge of the second card reaches a point between the ends of the third and fourth tongues 24 from the left, at which time brushes 40 and 41 will contact their "0" segments, a circuit will be established as follows: from negative side of source 17, wire 42, contacts 37, switch 38, wire 43, brush 40, "0" segment of commutator 40a, wire 52, points of relay A' (now closed), wire 53, "0" segment of commutator 41a, brush 41, wire 46, switch 39, wire 47, brush relay 10, sorting magnet 11, wire 48 to positive side of line 17. The three tongues in advance of the card will thereupon be lowered and this second card will continue into the gap so provided and will be conducted to the "0" sorting pocket 25. A parallel circuit as before will set up a holding circuit for relays B' and B to keep their respective points closed.

In this manner a circuit through the sorting magnet 11 and a parallel relay holding circuit will be completed for each card of the supposed group of eleven cards, at a time in their respective cycles which will be one point earlier than the time of completion of corresponding circuits in the cycle immediately preceding. Thus, as the last or eleventh card of the group approaches the tongues 24, the circuits will be completed through the "9" segments of commutators 40a and 41a and through the closed points of relay J' to drop all the tongues 24 and cause selection of the "9" sorting pocket 25. Relay K will incidentally be energized and a holding circuit therefor set up as for the other relays. Following this last pocket

selecting operation and toward the end of the cycle, commutator Z completes a circuit as follows: from positive side of source 17, wire 49, relay 51, brush 54, segment 55, brush 56, wire 57, closed points of relay K, wire 50, brushes 58 of commutator Y (now bridged by segment 59), wire 43, switch 38, contacts 37, wire 42 to negative side of source 17. Relay 51, upon energization, opens its points 51a and closes its points 51b, the latter setting up a holding circuit for relay 51 as follows: from positive side of source 17, wire 49, relay 51, points 51b, wire 60, brushes 61 of commutator X bridged by segment 62, wire 43 to negative side of source as before. Opening of points 51a will open the common holding circuit of the relays A-K and transfer it to the control of segment 59 whose brushes 58 are wired in shunt across points 51a. When brushes 58 break connection, however, the relays A-K are still held by a circuit from negative side of line to wire 43, brushes 61 and segment 62 of commutator X, closed points 51b of relay 51, brushes 54, 56 and 75

segment 55 of commutator Z, wire 57, relay K, wire 49 to positive side of source 11. When segment 55 leaves brushes 54 and 56, relays A—K and A'—J' will become deenergized and will permit opening of their respective points, the breaking arc at the segment 55 being dissipated in the condenser which is wired in shunt across brushes 54, 56.

At the completion of the eleventh card cycle 0 the circuits will be in readiness to distribute the eleven cards of the second group in the same manner as before, the process being repeated for each succeeding group until the supply of cards is exhausted or the machine is otherwise stopped.

5 Several switches 65a, 65b, and 65c are provided which may be closed if the number of cards in the groups to be distributed is less than 11. Thus, if the groups comprise eight cards, switch 65a may be closed and immediately following the 10 selection of a sorting pocket for the eighth card (at which time the points of relay H close) the commutator Z will complete a circuit as follows: from positive side of source 11, wire 49, relay 51 to brush 54, segment 55, brush 56, wire 57, switch 20 65a, closed points of relay H, wire 50, brushes 58 of commutator Y, wire 43, switch 38, contacts 37, wire 42 to negative side of source 11. From this 25 point the ensuing circuits will be identical with those described above in connection with the last 30 card of the eleven card groups.

With switch 65b closed, nine-card groups will be automatically distributed and with switch 65c closed, ten-card groups will be distributed into ten sorting pockets.

35 Fig. 3 shows a modified form of circuit arrangement whereby groups of cards which comprise a variable number of individual cards may be similarly distributed so that the first cards of all groups enter one pocket, the second cards enter a second pocket, and so on. The last card of each 40 group is identified by a special perforation in the "12" index point of a predetermined column as at 70 in Fig. 2 and this special perforation will affect the machine circuits in the same manner 45 as the relay points of relays I, J or K in the preferred form. That is, sensing of hole 70 will cause deenergization of such relays A—K that have been set up and condition the machine to feed the card immediately following into the 50 pocket which receives all the first cards of the groups.

For this operation the parts shown in heavy lines in Fig. 3 have been added to the circuit of Fig. 1 and with switch 71 in the position shown 55 and brush 22 located to traverse the card column containing hole 70 a circuit will be completed at the "12" time in the cycle as follows: from positive side of source 11, wire 72, relay 73, wire 74, switch 71, brush 22, hole 70, contact roller 30, wire 15, brush 14, commutator 13, brush 16, wire 18 to negative side of source 11. Energization of relay 73 will close its points 73a and connect wires 50 and 51 at the time when segment 55 of commutator Z bridges brushes 54, 56. The circuit 60 to relay 51 will thereupon be completed following which, as explained in detail above, relays A—K and A'—J' are reset and operations will take place on the next group to feed the next card into the pocket assigned to the first cards of the 65 groups. In this manner groups having indeterminate numbers of cards will be distributed so that all cards of the same sequential allocation will be sorted into a common pocket. The closure 70 of points 73a under control of the special hole 70 will therefore have the same effect as the closure 75

of the points of relay K in the preferred form where eleven cards are contained in each group and where the closing of such points serves to complete the connection between wires 50 and 51.

While there has been shown and described and pointed out the fundamental novel features of the invention as applied to two modifications, it will be understood that various omissions and substitutions and changes in the form and details of the device illustrated and in its operation may be 10 made by those skilled in the art without departing from the spirit of the invention. It is the intention therefore to be limited only as indicated by the scope of the following claims.

What is claimed is as follows:

1. In a sorting machine of the class described, a plurality of sorting pockets, each selectable in response to a differently timed electric impulse, means for emitting a series of differently timed impulses corresponding in number to said pockets, a circuit partly established for each impulse and means controlled by one of said circuits upon completion for completing the establishment of another of said circuits.

2. In a sorting machine of the class described, a plurality of sorting pockets, each selectable in response to a differently timed electric impulse, means for emitting a series of differently timed impulses to select each of said pockets in succession, means effective upon selection of the last of said pockets for causing repeated emission of said series of impulses and means for selectively suppressing the effectiveness of one or more of said impulses.

3. In a machine of the class described, means for feeding a plurality of groups of cards each having a different number of cards, a plurality of sorting pockets, means for effecting a series of selecting operations equal in number to the number of cards in a group whereby a separate pocket 40 is selected for each card of a group, means cooperating with said last named means for initiating a separate series of selecting operations for each group and for causing each series of operations to select a number of pockets equal to the number 45 of cards in the corresponding group.

4. In a machine of the class described, means for feeding a plurality of groups of cards each having a different number of cards, a plurality of sorting pockets, means for effecting a series of 50 selecting operations for successively selecting a different pocket for each card of the first group, means cooperating with said selecting means and controlled by the last card of the first group for causing a repetition of said series of operations whereby a pocket is selected for each card of the second group, said cooperating means being adapted to be controlled by the last card of said second group to terminate the second series of selecting operations after the selection of a pocket 60 for each card of the second group.

5. In a machine of the class described, means for feeding a plurality of groups of cards, each having a different number of cards, a plurality of sorting pockets, means for initiating a separate series of selecting operations for each group of cards fed through the machine to cause the selection of a separate pocket for each card of a group and means cooperating with said cards for limiting the number of operations in each 65 series to the number of cards in the corresponding group.

6. In a machine of the class described, means for feeding a plurality of groups of cards, each having a different number of cards, a plurality 70

- of pockets, selecting means therefor operable in response to timed electric impulses for selecting said pockets in succession, an emitter adapted to emit a series of timed electric impulses, one for each pocket, to control said selecting means, and means operable in response to the feeding of each group of cards for rendering effective only a number of impulses equal to the number of cards in a group.
10. 7. In a machine of the class described, means for feeding a plurality of groups of cards, each having a different number of cards, a plurality of pockets, pocket selecting means operable in response to timed electric impulses for selecting a different pocket in response to different impulses, means for emitting a series of timed impulses and means controlled by one of the cards of each group for selecting for effective operation a number of said impulses equal to the number of cards in said groups whereby the selected impulses will control the selection of a different pocket for each card of the group.
15. 8. In combination, in a sorting machine, a plurality of sorting pockets, means for feeding record cards successively, pocket selecting mechanism, record analyzing mechanism adapted to control
20. 9. In a cyclically operated machine of the class described, a plurality of sorting pockets, pocket selecting mechanism, means for feeding a card to said mechanism for each cycle of the machine, a plurality of controlling circuits, one for each pocket, a commutator device for completing said circuits at different times during a cycle and means controlled by each of said circuits and cooperating with said commutator for causing another of said circuits to control the operation of said selecting mechanism.
25. 2
